UNITED STATES PATENT OFFICE.

STEPHEN J. REAP, OF OLYPHANT, PENNSYLVANIA.

CAR-CHOCKING MEANS FOR MINE CAGES.

Application filed June 1, 1926. Serial No. 112,999.

The invention relates to improvements in chocks designed primarily for use on mine cages to hold cars in proper position thereon, while permitting one car to leave the cage 5 and another to enter the same, when the desired landing is reached, and while I am aware that numerous chock arrangements have been provided for this purpose, it is the object of the present invention to provide a new and improved construction and arrangement of parts which is mounted upon the cage and hence leaves the portions of the landings, adjacent the shaft, free of trips, levers and other accoutrements.

With the foregoing in view, the invention resides in the novel subject matter herein-after described and claimed, the description being supplemented by the accompanying drawings.

Fig. 1 is a side elevation of a portion of a mine cage, showing the application of the invention thereto.

Fig. 2 is a bottom plan view.

Fig. 3 is a vertical transverse section on line 3—3 of Fig. 1.

Fig. 4 is a longitudinal sectional view as indicated by line 4—4 of Fig. 2.

Fig. 5 is a fragmentary top plan view showing two of the chocks in operative relation with the cage rails in full lines and in dotted lines showing the positions in which they are latched by a portion of the invention to permit free travel of a car from the cage.

"C" designates a mine car cage and "S" has reference to the usual mine shaft. The cage shown includes a deck "D" supported by a frame structure "F", said frame structure comprising side bars 6, end bars 7, and transverse bars 8 inwardly spaced from said end bars, and it will be observed from a number of the views, that the deck carries the usual rails "R" for alignment with stationary rails at the several landings.

At one end of the deck D and mounted to swing either over the rails R or outwardly away from these rails are two wheel chocks 9 while a similar pair of chocks 9' are mounted at the opposite end of the cage, these chocks being adapted for engagement with the wheels W of a mine car to hold the latter upon the cage while the car is being raised or lowered. The chocks 9 and 9' are carried by vertical shafts 10 and 10' which pass through the deck D and have crank

arms 11 and 11' on their lower ends. The crank arms 11 and 11' are connected by links 12 and 12' respectively, with pairs of transverse horizontal levers 13 and 13' which are disposed under the deck D and are fulcrumed between their ends upon appropriate brackets 14 which are secured to the end bars 7 of the frame F. The inner ends of the levers 13 are pivoted to a link 15 whose inner end is pivoted at 16 to a crank arm 17 rising from a transverse rock shaft 18 at one end of the cage C. Similarly, the inner ends of the levers 13' are pivotally connected with the outer end of a link 15', the inner end of the latter being pivoted at 16' to a crank arm 17' on a transverse rock shaft 18' mounted near the opposite end of the cage. Separate actuators are provided for the operating mechanisms of the two sets of chocks 9 and 9', these actuators being shown in the form of rigid arms 19 and 19' projecting outwardly from the shafts 18 and 18' respectively, and adapted upon predetermined lowering of the cage, to engage and be upwardly swung by suitable trips in the shaft. These trips may be of any desired nature and they are merely illustrated in a diagrammatical way at 20 and 20' in Fig. 1. They are of course mounted so that they may be projected or retracted individually, as occasion may demand. When the trip 20 is projected to its operative position, it is in the downward path of the arm 19 and when this arm strikes said trip, it swings upwardly to the dotted line position of Fig. 1. In moving in this manner, the arm 19 turns the shaft 18 causing the arm 17 to inwardly pull upon the link 15, thus rocking the levers 13 and causing the links 12 to pull upon the crank arms 11 of the shafts 10, thereby swinging the chocks 9 outwardly away from the rails R. By the time, the arm 19 has passed the trip 20, these chocks 9 have been outwardly swung to an extreme position beyond a wheel clearing position and provision is made for holding them in such extreme position. By the time this holding has taken place, the cage has reached a landing and the released chocks will permit the cage-carried car to be forced from one end of the cage by another car forced onto said cage from the other end, and the shaping of the chocks is such that the car entering the cage will outwardly swing the chocks 9', novel provi-

sion being made whereby this outward swinging to a wheel-clearing position, will automatically release the latching means which previously held the chocks 9 in the 5 extreme position shown in dotted lines in Fig. 5, the result being that these chocks 9 then return to their initial operative positions, under the influence of gravity acting on certain of the operating parts. This re- 10 turn of the chocks has taken place before the wheels of the car being moved onto the cage, reach the point at which said chocks are located, so that the car is then stopped by said chocks. As soon as this 15 takes place, the chocks 9' return to their initial positions and thus the car is effectively locked upon the cage.

If the cars are to be moved in the opposite direction from that above described, trip 20 20' is relied upon to actuate the arm 19' and associated parts, so that the chocks 9' are held in extreme inoperative positions. When the approaching car then engages the chocks 9, during the act of pushing the cage-carried car from the cage, said chocks 9' are automatically released to return to normal position, and later the chocks 9' return also, to hold the car in place upon the cage.

In the present showing, latching bars 21 30 and 21' are disposed longitudinally under the cage and are pivotally connected to the crank arms 17 and 17' respectively, these latching bars being pivoted to the bars 15 and 15' in the present disclosure, utilizing the pivots 16 and 16' to pivotally connect them with the crank arms. The bar 21 extends beyond the shaft 18' and is slidably received in a guide 22' on one of the transverse bars 8. Similarly, bar 21' extends beyond the shaft 18 and is slidably mounted in a guide 22 carried by the other transverse bar 8. The upper edges of these two latching bars 21 and 21' are provided with shoulders 23 and 23' which are adapted for 40 engagement with two pivoted latches 24 and 24' respectively, each in the form of a bell crank, as will be clear from Fig. 3, said latches being pivoted upon appropriate brackets 25 which are secured to the bars 50 8. Normally, that is when all of the chocks 9 and 9' are projected, the latch 24 rests upon the upper edge of the latching bar 21, in outwardly spaced relation with the shoulder 23. Similarly, the latch 24' then rests 55 upon the outer end of the bar 21', in outwardly spaced relation with the shoulder 23'. If now, shaft 18 is turned to the maximum to effect outward movement of the chocks 9 to an extreme position beyond a mere car wheel clearing position, the bar 21 is moved sufficiently to permit the latch 24 to engage the shoulder 23, thus effectively holding said chocks 9 in said extreme position. Similarly, the latch 24' engages 60 shoulder 23' upon maximum movement of

the bar 21', when shaft 18' is turned to outwardly swing the chocks 9' to their extreme positions.

Latch-releasing arms 26 and 26' are provided for the latches 24' and 24, respectively, the arm 26 being on one of the levers 13 while arm 26' is on one of the levers 13'. These arms 26 and 26' are in contact with the vertical arms 24^a—24^b of the bell cranks or latches 24' and 24, respectively. To understand the action of these releasing arms, we will assume that the chocks 9 are held in their extreme outward positions by engagement of the shoulder 23 with the latch 24, and that a car is forced onto the cage to move the cage-carried car between said chocks 9 and off of said cage. The oncoming car engages and outwardly swings the chocks 9', causing movement of the lever 13' and associated parts, so that the arm 26' then forces against the vertical arm 24^b of the bell crank or latch 24, raising the latter from engagement with the shoulder 23 of the latching bar 21. By this time, the off-going car is clear of the chocks 9 and the latter are thus free to return to operative position, to check the movement of the ongoing car, and by the time the wheels of this car have passed the chocks 9', the latter return to their initial operative positions. At 90 this point, it may be explained that the outward movement of the chocks 9' under the influence of the wheels of the oncoming car was not sufficient to move the bar 21' sufficiently to cause engagement of its shoulder 23' with the latch 24', said chocks being therefore left free to return to normal position, when the car wheels have passed. If the chocks 9' have been shifted outwardly to their extreme positions and latched by engagement of latch 24' with shoulder 23', release of this latch will take place when the chocks 9 are outwardly moved by engagement with the car wheels, as will be readily understood.

It often happens that it is necessary to hold both sets of chocks in released position, so that cars may travel uninterruptedly over the cage. Manual operating connections are therefore provided for the actuators 19 and 19'. In the present showing, links 27 and 27' have sliding connections 28 and 28' with said actuators 19 and 19', the upper ends of these links being connected to pivoted arms 29 and 29' having operating handles 30 and 30' respectively. The connections 28 and 28' permit upward movement of the actuators 19 and 19' under the influence of the trips 20 and 20', without disturbing the links 27 and 27', and associated parts. When the levers or handles 30 and 30' are swung upwardly however, they will upwardly swing both actuators and thus move the chocks to inoperative positions, and if desired, openings 31 and 31' may be provided, through 130

which pins may be inserted to lock the hand-controls in such position as to retain the chocks released.

The novel subject matter shown and described is rather simple and inexpensive, yet will be efficient, reliable, and in every way desirable. On account of such advantages, the details disclosed are preferably followed. However, within the scope of the invention as claimed, variations may be made.

I claim:—

1. In combination with a vertically movable cage having track rails for alinement with rails at a landing; a normally operative car wheel chock at each end of the cage separate operating mechanisms for said chocks having independent actuators by means of which said mechanisms can be selectively actuated to move the chock at either end of the cage to an extreme position beyond a wheel-clearing position, independent latch means for the two operating mechanisms to hold either of them only in a manner to retain the associated chock in the aforesaid extreme position, each chock being shaped for movement to but not beyond said wheel-clearing position when engaged by a wheel of a car forced onto either end of the cage to move a cage-carried car from the other end of said cage, and means actuated by the last named or wheel-effected movement of either chock and the concurrent movement of its operating mechanism for releasing the latch means of the other chock operating mechanism, permitting return of the previously held chock to operative position.

2. In combination with a vertically movable cage having rails for alinement with rails at a landing; a normally operative car wheel chock at each end of the cage, separate operating levers for said chocks ful-

crumed to the cage and extending transversely thereof, the outer ends of said levers being operatively connected with said chocks, transverse rock shafts mounted on the cage near the ends thereof and having crank arms linked to the inner ends of said levers actuating arms projecting from said rock shafts, the actuating arm at either end of the cage being active to move the chock at said end to an extreme position beyond a wheel-clearing position, two latching bars extending longitudinally of the cage and connected with said crank arms of the rock shafts respectively, two latches for said bars mounted on the cage adjacent the aforesaid levers, the latch at either end of the cage being co-active with the latching bar connected to the rock shaft at the other end of said cage to hold the chock at the latter end in said extreme position, each chock being shaped for movement to but not beyond said wheel-clearing position when engaged by a wheel of a car forced onto the cage to move a cage-carried car from the other end of said cage, and releasing means for said latches, movement of either rock shaft under the last mentioned or wheel-effected movement of the connected chock serving to release the latch of the latching bar connected to the other rock shaft permitting the previously held chock to return from said extreme position to operative position.

3. A structure as specified in claim 2; 75 said latch-releasing means consisting of arms projecting from said transverse levers.

4. A structure as specified in claim 1; together with manual operating means for said actuators, and means whereby they may be locked in chock-released position.

In testimony whereof I have hereunto affixed my signature.

STEPHEN J. REAP.
